UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

GRAIN-CAR DOOR.

1,405,666.

Specification of Letters Patent. Patented Feb. 7, 1922.

Application filed September 18, 1920. Serial No. 411,240.

To all whom it may concern:

Be it known that I, ARGYLE CAMPBELL, a citizen of the United States, residing at Chicago, in the county of Cook and State of Illinois, have invented a certain new and useful Improvement in Grain-Car Doors, of which the following is a full, clear, concise, and exact description, reference being had to the accompanying drawings, forming a part of this specification.

This invention relates to improvements in grain car doors.

The object of the invention is to provide a simple efficient and economical arrangement of grain doors for railway box cars, the arrangement being such that the grain doors, when the car is used for carrying loads other than grain or other bulk materials, may be readily positioned in the car in such a way as to avoid interference with loading of the car and without occupying any of the normal loading space of the car.

Other objects of the invention will more clearly appear from the description considered in connection with the drawings, hereinafter following.

In the drawings forming a part of this specification, Figure 1 is an inside elevational view of a box car adapted for the carrying of grain and showing my improvements in connection therewith. The full lines indicate the position of the two grain doors in position across the usual side door opening and the dotted lines indicate the position assumed by the doors when not in use. Figure 2 is a horizontal sectional view corresponding substantially to the line 2—2 of Figure 1. Figure 3 is a vertical broken sectional view corresponding substantially to the line 3—3 of Figure 1. And Figure 4 is a detail sectional view corresponding substantially to the line 4—4 of Figure 1.

In said drawings, the box car is shown as having a side wall composed of a single heavy wood sheathing 10 braced on the exterior thereof by Z-bar posts 11 and diagonal braces 12 in a well known manner. The usual side door opening, indicated at 112 is shown, the same being defined by a threshold 13, lintel 14 and jambs 15—15. The jambs have applied thereto interior facing strips 16—16 in the usual manner.

In the ordinary construction of cars of the single sill types, such as shown in the drawing, the wood sheathing extends to the

door jambs. In order to enable me to position the grain doors, when the latter are not in use, clear of the interior of the car and without occupying any of the usual loading space, I remove or omit those portions of the wood sheathing 10 between the door jambs and the posts 11 which are nearest thereto, as shown most clearly in Figure 2 and substitute for the wood sheathing thus removed or omitted, sheet metal panels 17—17 which are applied at their edges to the outer face of the wood sheathing so as to leave recesses 18—18 immediately adjacent the door opening on each side thereof. As will be obvious, the depth or horizontal dimension of 18 said recesses 18 will correspond to the thickness of the wood sheathing which in ordinary practice is usually one and three quarter inches.

In carrying out my invention, I employ two grain doors A and B. Each of said doors A and B may be of any desired substantial construction but preferably each consists of a plurality of horizontally extending boards 19—19 bound around their vertical edges by U-shaped sheet metal binding strips 20—20. Diagonally extending battens of plate or metal strap form are also preferably employed. The various boards or planks are preferably shiplapped and the top edge of the bottom door A and lower edge of the upper door B are also preferably shiplapped as indicated at 22 in order to prevent leakage of grain. As clearly shown in Figure 1, the doors are of such a width as to extend across the door opening 112 and also overlap the interior facing strips 16.

The lower door A is pivotally attached by means of a hinge butt 23 through which extends a horizontally arranged elongated fixed bolt 24. The bolt 24 is preferably countersunk as indicated at 25 in Figure 1 so that the bolt and the anchor casting to which it is secured will be below the floor level and substantially free from any injury from trucking or placing or removing of the load. The hinge mounting for the door A is at one lower corner as clearly indicated in Figure 1 and the axis of the pivotal connection is slightly to one side of the corresponding door jamb and facing strip so as to adapt the door to be swung to a vertical position as indicated by the dotted lines A' in Figure 1. When swung to said vertical position, the door A may then be shifted inwardly of

the bolt 24 within the recess 18 so as to lie flat against the sheet metal panel 17 as best indicated in Figure 2. The door may be held in this vertical inoperative position by 5 any suitable means such as a pivoted latch 26 and pin 27.

In the case of the upper door B, the pivotal connection is at a lower corner but on the opposite side of the door opening to that 10 of the pivotal mounting of the lower door A. In the case of the door B, a diagonally downwardly extending hinge bracket 28 is used, the same being mounted on a horizontally extending elongated bolt 29. The head 15 of the bolt 29 is vertically adjustably mounted in a guiding casting 30 having a vertically extending slot 31 through which the bolt is permitted to slide within the casting 30. The guiding casting 30 is secured to the 20 corresponding sheet metal panel 17. The hinge butt 28 is made elongated as clearly indicated in Figure 4 and the bracket 30 is so positioned as to bring the bolt 29 an appreciable distance away from the adjacent 25 door jamb and facing strip. This is done in order to permit the door B, when it is swung clear of the door opening 112, to be moved outwardly against the panel 17 to the position indicated by the dotted lines B' in Figure 4. In other words, the vertical edge 32 of the door B, when it is in the dotted line position B', is clear of the guiding bracket 30 and hence will leave the inner face of the 30 door B flush with the inner face of the wood sheathing 10. The guiding bracket 30 is extended downwardly a short distance within the floor 33 so that, when the door B is in its inoperative position, the bolt 29 will enter the slot 34 in the floor and be free from 35 danger or injury as in the case of the other pivotal connection, heretofore described. The door B can be held in its inoperative position in any suitable manner as by a pivoted latch 35 and pin 36.

40 The width of the side door openings and the height of the roof above the floor of box cars varies and it is on account of these facts that the door B is mounted by means of an adjustable pivotal connection. Where the 45 side door opening of the car is narrow and the roof comparatively high above the floor, no difficulty would be experienced in swinging the upper door B about a fixed pivot but where the door opening is unusually wide 50 or the roof is comparatively low, it would be impossible to swing the upper door about a fixed pivot. With my construction of adjustable pivotal attachments for the upper door, I am enabled to employ the same on all 55 types of cars regardless of the variations and dimensions referred to since, in swinging the upper door B about its pivotal connection, the pivotal connection may be gradually lowered during the pivotal movement so as 60 to avoid any possible interference or en-

gagement with the roof, as will be understood.

When a car is filled with grain the pressure against the grain doors is such that it is almost impossible to open the grain doors 70 unless the pressure is relieved against the inner side of the grain doors. Some railroads prefer a relief door as indicated conventionally by dotted lines at 37 in Figure 1 in the lower door A and other railroads 75 prefer a grain relief discharge chute as indicated conventionally at 38 in Figure 3, to accomplish this result. Either practice may be employed in connection with my improvements.

80 I have herein shown and described what I now consider the preferred manner of carrying out my invention but the same is merely illustrative and I contemplate all changes and modifications that come within the scope 85 of the claims appended hereto.

I claim:

1. A grain car having a side door opening; and a pair of inside grain doors adapted to partially close said door opening and arranged to be positioned one above the other when in operative position, the lower of said doors being pivotally attached at a relatively fixed point to the car at one of its lower corners, the upper door being pivotally attached 90 at its lower corner on the opposite side of the door opening, said last named pivotal connection being adjustable to permit the upper door to be bodily lowered to the floor when swung to an inoperative position.

100 2. In a grain box car, the combination with the side wall thereof having a side door opening, said wall having a recess provided on the inner side thereof immediately adjacent one side of the door opening; of an inner door adapted to be horizontally positioned across the door opening when in operative position, said door being pivotally attached at one of its lower corners to said side of the door opening and arranged to permit the 110 door to be swung in a vertical plane, the door being horizontally inwardly and outwardly adjustable on its pivot relatively to the side wall of the car so that, when the door is swung clear of the door opening, it may be 115 positioned within said recess of the car wall.

120 3. In a railway box car adapted for the carrying of grain and the like, the combination with a side wall thereof having a door opening, said side wall having recesses on the inner side thereof on each side of the door opening and immediately adjacent the latter; of a pair of inner doors adapted to be positioned across said door opening, one above the other, each of said doors being pivotally 125 attached to said car wall, one at one side of the door opening and the other at the opposite side thereof on the inner side of the wall, each pivotal connection of the doors permitting of horizontal adjustment inwardly and 130

outwardly with respect to the car wall whereby, when the doors are swung to inoperative position, each is adapted to be seated in one of said recesses.

- 5 4. In a railway box car adapted for the carrying of grain and the like, the combination with a side wall thereof having a door opening, said side wall having recesses on the inner side thereof on each side of the door opening and immediately adjacent the latter; of a pair of inner doors adapted to be positioned across said door opening, one above the other, each of said doors being pivotally attached to said car wall, one at one side of the door opening and the other at the opposite side thereof on the inner side of the wall, each pivotal connection of the doors permitting of horizontal adjustment inwardly and outwardly with respect to the car wall whereby, when the doors are swung to inoperative position, each is adapted to be seated in one of said recesses, the pivotal connection for the upper door being also vertically adjustable.
- 25 5. A railway box car adapted for the carrying of grain and the like, said car having a side wall provided with a door opening therein, said wall being composed mainly of wood sheathing and exterior posts and braces, the portions of the side walls on opposite sides of and immediately adjacent the said door opening comprising sheet metal panels extending between the door jambs and the respective nearest posts, the sheet metal panels being disposed on the outer side of the wood sheathing whereby to leave recesses on

each side of the door opening; of a pair of inner doors adapted to partially close said door opening when in operative position; and adjustable means connecting each of said doors to the car structure at opposite sides of the door opening, said means adapting each door to be positioned within a recess when not in use.

6. The combination with a railway box car adapted for the carrying of grain and the like, said box car having a side wall composed mainly of wood sheathing and exterior posts and braces, said side wall having a side door opening therein, the portions of the side walls immediately adjacent the door opening on each side thereof consisting of sheet metal panels; of a lower grain door pivotally attached at one of its lower corners to the car structure at one side of the door opening and about which pivot the door is adapted to be swung in a vertical plane to a position opposite one of said sheet metal panels; of a second grain door pivotally connected at one of its lower corners to the car structure at the opposite side of the door opening, said last named pivotal connection being vertically adjustable and adapting the door to be swung in a vertical plane to a position opposite the other of said sheet metal panels.

In witness that I claim the foregoing I have hereunto subscribed my name this 4th day of Sept., 1920.

ARGYLE CAMPBELL.

Witness:

CARRIE GAILING.
